CLAIM

The ornamental design for a bag strap connector, as shown and described.

DESCRIPTION

FIG. 1 is a top perspective view of the first embodiment of a bag strap connector;

FIG. 2 is a front elevational view of the bag strap connector of FIG. 1;

FIG. 3 is a rear elevational view of the bag strap connector of FIG. 1;

FIG. 4 is a top view of the bag strap connector of FIG. 1;

FIG. 5 is a bottom view of the bag strap connector of FIG. 1;

FIG. 6 is a right side view of the bag strap connector of FIG. 1;

FIG. 7 is a left side view of the bag strap connector of FIG. 1;

FIG. 8 is a top perspective view of a second embodiment of the bag strap connector shown in FIG. 1;

FIG. 9 is a front elevational view of the bag strap connector of FIG. 8;

FIG. 10 is a rear elevational view of the bag strap connector of FIG. 8;

FIG. 11 is a top view of the bag strap connector of FIG. 8;

FIG. 12 is a bottom view of the bag strap connector of FIG. 8;

FIG. 13 is a right side view of the bag strap connector of FIG. 8; and,

FIG. 14 is a left side view of the bag strap connector of FIG. 8.

The broken lines are included for the purpose of illustration only. None of the broken lines forms part of the claimed design.
